US00D890006S

(12) **United States Design Patent** (10) Patent No.: **US D890,006 S**
Takano et al. (45) Date of Patent: ** Jul. 14, 2020

(54) **SENSOR HOUSING**

(71) Applicant: **YOKOGAWA ELECTRIC CORPORATION**, Tokyo (JP)

(72) Inventors: **Naoto Takano**, Tokyo (JP); **Xiaojian Guo**, Tokyo (JP); **Yuuta Oohara**, Tokyo (JP)

(**) Term: **15 Years**

(21) Appl. No.: **35/506,478**

(22) Filed: **Sep. 27, 2018**

(80) **Hague Agreement Data**

Int. Filing Date: **Sep. 27, 2018**

Int. Reg. No.: **DM/200082**

Int. Reg. Date: **Sep. 27, 2018**

Int. Reg. Pub. Date: **Mar. 29, 2019**

(51) **LOC (12) Cl.** **10-05**

(52) **U.S. Cl.**

USPC **D10/104.1**

(58) **Field of Classification Search**

USPC D10/70, 47; D14/216, 209, 496
